UNITED STATES PATENT OFFICE.

FRANCIS M. HOFFMAN, OF DETROIT, MICHIGAN.

WIRE-SUPPORTING ARRANGEMENT.

Application filed December 27, 1927. Serial No. 242,924.

This invention relates to wire supporting arrangements, and consists essentially in an arm bracket having two piece insulators mounted thereon. The invention aims, among other things, to provide a wire supporting arrangement wherein no parts have to be detached in order to place wires between the insulator portions, and consists in the provision of insulator portions slotted from one end and corresponding slots in the arm bracket extending beyond the slotted insulator ends so that bolts extending through the arm slots may either engage the insulator slots and have their nuts tightened against the upper insulator portions, or else be moved clear of the insulator portions so that the latter may be moved pivotally about other bolts which pass through the said arm and the opposite ends of the insulator portions.

A preferred embodiment of the invention is hereinafter more fully described with the aid of the accompanying drawings, in which:

Figure 1 illustrates a front view of the invention, and

Figure 2 is a side view thereof.

Referring to the drawings, 1 designates an arm bracket, which may be arranged either vertically, as shown, or horizontally. In the present instance it is provided with a hole 2 to receive a bolt 3 by which it is secured to a support 4, though any other preferred means may be employed for mounting the said arm bracket.

Through the arm bracket 1 a plurality of holes 5 and slots 6 are cut. The holes are preferably square to receive the square shanks 7^a of the bolts 7 and through the slots are other bolts 8. The upper and lower insulator portions 9 and 10, which are similar, have slots 11 and 12 extending longitudinally therethrough from one end, and holes 13 and 14 through their opposite ends for the passage of the bolts 7. In the inner sides of the insulators opposed grooves 15 and 15^a are provided to receive the wires as shown at 16.

Before the arm bracket is installed it is usual to place the insulator portions 9 and 10 in position and insert the bolts 7 through the holes 5, 14 and 13, and the bolts 8 through their slots 6. The bolts 8, the nuts 8^c on which are loose, may then be moved longitudinally in their slots 6 into the position

indicated at 8^b to free the insulator portions so that they may be turned pivotally about their bolts 7. The upper insulator portion 9 is then turned into the position indicated at 9^a so that the wire 16 may be inserted into its lower groove 15. The said portion 9 is then turned back to cover its lower portion 10 and then the bolt 8 is moved into engagement with the slots 11 and 12. The nuts 7^c and 8^c should then be tightened.

From the foregoing it will be clearly seen that a simple and effective means has been devised for holding the insulator portions so that no parts need be detached in order to place wires in position between the said portions.

What I claim is:

1. An arrangement of the character described comprising an arm bracket, means for supporting said bracket, upper and lower insulator portions one overlying the other, means towards one end of said portions for mounting them pivotally on said arm bracket, said portions having slots therethrough extending from their opposite ends, said arm bracket having a slot therethrough registering with said first named slots and extending beyond the latter, a bolt through said arm bracket slot adapted to hold said insulator portions in position when in engagement with said insulator slots or to be moved clear of the latter to permit the said portions to be moved about said first named bolt, and means for holding a wire between the adjacent faces of said portions.

2. An arrangement of the character described comprising an arm bracket having a hole and a slot therethrough, an upper and a lower insulator portion each having a hole therethrough registering with said arm bracket hole, a bolt extending through all three holes, said insulator portions also having slots therethrough from one end which register with part of said arm bracket slot, the latter extending beyond said insulator portions, said portions in their contiguous sides having opposed recesses adapted to receive a wire, and another bolt through said arm bracket slot adapted to extend through the slots in said insulator portions or to be moved clear of said portions so that the latter may be turned pivotally about said first named bolt.

FRANCIS M. HOFFMAN.
